UNITED STATES PATENT OFFICE

ADAM BAUER, OF MUNICH, GERMANY

FASTENING FOR GARMENTS

Application filed May 27, 1926, Serial No. 112,020, and in Germany June 4, 1925.

My invention relates to waist bands for trousers and more particularly to waist bands with a belt housed therein. It is an object of my invention to provide a waist band of this type in which pressure on the stomach and the tendency of the trousers to sag at the fly, are eliminated.

To this end, instead of arranging the buckle of the belt in line with the fly as usually, I provide a slit in the waist band at one side of the fly so that part of the waist band, with the belt housed therein, extends from the fly to that side of the slit, and in the slit I arrange the buckle of the belt. In this manner a pull is exerted on the belt in the region of the fly which prevents sagging.

In the drawings affixed to this specification and forming part thereof my invention is illustrated diagrammatically by way of example.

In the drawings

Fig. 1 is a front elevation,

Fig. 2 is a rear elevation of the upper portion of a pair of trousers,

Fig. 3 shows the fly opened and

Fig. 4 is a detail illustration of the belt.

Referring to the drawings *a* is the waist line of the trousers and *b* is the waist band arranged along this waist line in which a belt *c* is inserted for free displacement. At the back the waist band is preferably intersticed for a distance of about 4 in., exposing the belt. The interstice is provided for facilitating the insertion of the belt and to prevent puckering of the trousers when the belt is drawn more tightly.

The buckle of the belt projects from another interstice *e* in the waist band which is arranged at one side of the fly and is about 2 in. wide. *h* is the section of the waist band which extends between the buckle and the fly. It will be seen that the major portion of the waist band *b* extends from the free edge of the fly across the seam connecting the fly to the body of the garment, and, as shown, to the rear interstice, and that the section *h* extends in the opposite direction from adjacent the edge of the fly such a distance that the buckle *f* must be

positioned relatively remote from the fly and adjacent the hip of a person wearing the trousers. In this manner the belt positively supports the trousers in the immediate vicinity of the fly at the right and the left side of the fly so that when drawing the belt the trousers are supported at both sides of the fly and an upward pull is exerted at this point.

The closure of the belt *c* comprises a buckle *f* which is slotted at *g* and a hook adapted to engage the slots so that the belt may be adjusted.

The belt is permanently retained in the trousers and when it is desired to open the trousers the portion of the belt to which the slotted buckle *f* is secured is pulled from the short section *h* of the waist band *b* to the right and upon closing the trousers it is pushed back through the section *h* and the hook at its opposite end is inserted in one of the slots *g* of the buckle *f*.

I wish it to be understood that I do not desire to be limited to the exact details of construction shown and described for obvious modifications will occur to a person skilled in the art.

I claim:

A pair of trousers having its waist band provided with belt supporting means including two elongated tubular portions, one extending across the fly to a point beyond the seam connecting the fly to the body of the garment, and the other said portion extending, in the opposite direction, from adjacent the edge of the fly such a distance that the fastening means of a belt passing through said tubular portions must be positioned relatively remote from the fly and adjacent the hip of a person wearing the trousers.

In testimony whereof I affix my signature.

ADAM BAUER.
